J. F. LEIDECKER

DETACHABLE BUTTON

Filed March 29, 1923

FIG. 1.

FIG. 2.

FIG. 3.

FIG. 5.

INVENTOR
JOHN F. LEIDECKER.

BY
Harry J. Schweder
ATTORNEY

UNITED STATES PATENT OFFICE.

JOHN F. LEIDECKER, OF ALAMEDA, CALIFORNIA.

DETACHABLE BUTTON.

Application filed March 29, 1923. Serial No. 628,492.

To all whom it may concern:

Be it known that I, JOHN F. LEIDECKER, a citizen of the United States, residing at Alameda, in the county of Alameda and 5 State of California, have invented certain new and useful Improvements in Detachable Buttons, of which the following is a specification.

My invention is an improved detachable 10 button.

The object of my invention is to provide a button which is simple in construction and inexpensive to manufacture.

A further object is to provide a button 15 which will tenaciously grip the cloth and which may be readily attached and removed as desired.

In the drawing in which my invention is illustrated, I have shown the preferred form 20 but it may be embodied in other forms, and in this application I wish to cover my invention in whatever form it may be embodied.

Referring to the drawing:

Figure 1 is a side view of my button in 25 position in a piece of cloth.

Figure 2 is a front view of the gripping member.

Figure 3 is a rear view of the locking member.

30 Figure 4 is a side view of the same.

Figure 5 is a side view of the gripping member engaging the cloth.

Referring more particularly to the drawing, my button consists of a gripping member 35 1 and a locking member 2. The grip-

ping member 1 is formed of a pair of jaws 3 and 4 which are hinged together at 5—5. Teeth 6 and 7 extend from the jaws 3 and 4 respectively, and are adapted to engage the cloth to hold the button in place, as 40 shown in Figures 1 and 5. To engage the teeth 6 and 7 the jaws 3 and 4 are swung forwardly on their hinges 5—5, thus separating the teeth and enabling them to bite into the cloth when the jaws are again 45 swung together rearwardly. To hold the jaws 3 and 4 in their engaging position a locking member 2 is provided which consists of a surface plate 8 which may be of any desired shape or design; a groove 9 is 50 formed back of the plate 8 into which the outer edges of the jaws 3 and 4 are adapted to fit. The jaws are compelled to spring slightly in entering the groove 9 which holds them securely in place and in a locked position. 55

Having described my invention, I claim:

1. A button comprising a pair of jaws hinged together, teeth on said jaws, a locking plate, said plate having a groove therein, 60 the outer edges of said jaws being adapted to rest in said groove.

2. In a button comprising a pair of jaws connected to clamp the cloth, a locking plate comprising the face of the button having a 65 groove in the back thereof adapted to cooperate with the edges of said jaws.

In testimony whereof I affix my signature.

JOHN F. LEIDECKER.
